[57] **ABSTRACT**

A collapsible paperboard carton made from a single rectangular blank and having equal top and bottom panels spaced by a back panel equal to the front panel and front flap on the top panel, each of which panels have end flaps which extend outwardly only slightly more than half the height of the back panel. These end flaps have six creased triangular corners which are glued to the adjacent flaps so that the end flaps of the front and back panels form corner posts for the set-up carton. The end flaps of the top panel may have spaced notches to form a tuck-in flap between them for locking over the top edge of the end flaps of the bottom panel when the carton is set up. The back panel may be apertured for ventilation purposes.

SIX CORNER COLLAPSIBLE CARTON

BACKGROUND OF THE INVENTION:

Six corner glued Beer style paperboard cartons which are collapsible are well known, however, the blanks for these one-piece cartons usually comprise side panels having end flaps of different widths and accordingly there is wastage and/or nesting of the blanks in the sheet from which they are cut. Furthermore, these cartons often have ends formed of two fully overlapping flaps from two opposite side panels which requires larger area blanks.

SUMMARY OF THE INVENTION

Generally speaking, the six corner glued collapsible Beer style box of this invention has the following material improvements of only employing about half height ends hinged to both the top and bottom panels thereby materially saving board, and providing a rectangular blank which may be cut from sheets of board with substantially no wastage or need for nesting of the blanks. Furthermore the flaps on the front and back panels act as posts to strengthen the box so that the reduction in the amount of board in the ends does not weaken the box. Furthermore, if desired, notches may be provided in one of the end flaps, preferably the top, between which a locking flap is formed for snapping over the top edge of the bottom end flaps for locking the box in its closed position. Since boxes of this type are often used for packaging carry-out foods such as fried chicken and the like, apertures may be provided in one of the panels such as the back panel for ventilation purposes and for the escape of steam or vapors which may collect inside the carton when it is filled.

Specifically, the single piece blank for the carton of this invention comprises equal top and bottom rectangular panels spaced by a back panel having the height of the box hinged to adjacent edges of the top and bottom panels and a front panel equal to the back panel hinged to the front edge of the bottom panel. The top panel may have a similar front panel hinged to its front edge, however, such does not have to be of full height of the carton. Each of these five panels have hinged at their ends equally outwardly extending flaps. These flaps on the top and bottom panels provide half height sides for the ends of the carton and contain folded diagonal corners which are glued to the flaps on the front and back panels. Thus this carton is completely assembled where it is manufactured, shipped in a knocked down position, and easily set up just before being filled at its use location. Since the end flaps extend only slightly more than half the height of the back panel, the ends of the box are each half formed by the flaps at the ends of the top and bottom panels, while the end flaps on the front and back panels, when the carton is set up act as corner posts to strengthen the carton.

BRIEF DESCRIPTION OF THE VIEWS

The above mentioned and other features, objects and advantages, and the manner of attaining them are described more specifically below by reference to embodiments of this invention shown in the accompanying drawings, wherein:

FIG. 1 is a perspective view of one embodiment of the improved collapsible six corner glued carton of this invention assembled and in setup closed position with locking flaps at its ends, and showing in dotted lines how its top may be opened;

FIG. 2 is a plan view of the substantially rectangular blank employed in forming the carton shown in FIG. 1;

FIG. 3 is a front view of the carton shown in FIG. 1 in its collapsed or knock-down position for storage and/or shipping;

FIG. 4 is an end view of the collapsed carton shown in FIG. 3;

FIG. 5 is a back or rear view of the collapsed carton shown in FIG. 3;

FIG. 6 is a view similar to FIG. 1 of another embodiment of the carton of this invention in which no end locking flaps are employed and with full front corner post on the top panel; and

FIG. 7 is a plan view of the rectangular blank employed in forming the carton shown in FIG. 6.

DETAILED DESCRIPTION OF PREFERRED EMBODIMENTS:

Referring first to the embodiment shown in FIGS. 1 through 5, the carton or box is composed of a single folded blank 10 (FIG. 2) having glued corners on some of the flaps. This blank 10 comprises primarily the two larger rectangular panels 11 and 12 which form the bottom and top of the box, respectively. At the adjacent edges of these panels there is hinged along crease lines 13 and 14, respectively, back panel 15 which has a width equal to that of the height of the box. At the opposite front edges of the bottom and top panels 11 and 12, respectively, are two front panels 16 and 17 hinged along fold lines 18 and 19, respectively.

At the opposite ends of each of the panels 11, 12, 16 and 17 there are provided flaps hinged along parallel crease lines 20 and 21. Each of these flaps extends outwardly from these lines 20 and 21 slightly more than half the height or width of the back panel 15 or front panel 16, so that when the box is assembled the outer edges of the end flaps 22 and 23 on the bottom panel 11, and end flaps 24 and 25 on the top panel 12 will slightly overlap as shown in FIG. 1.

Both corners of the bottom end flaps 22 and 23 are provided with diagonal crease lines 26, 27 and 28, 29, respectively, which triangular portions are glued and attached to the corresponding adjacent portions of the end flaps 30, 31, 32, 33 on the front and back panels 16 and 15 as shown in FIG. 1. Thus the glued triangular portion adjacent the crease line 26 is attached to the adjacent portion of end flap 30 of the back panel 15, and the triangular glued portion adjacent the crease line 27 is attached to the adjacent portion of end flap 31 of the front panel 16. Similarly the triangular glued portion 28 is attached to the flap 32 of the back panel 15 and the triangular glued portion along the fold line 29 is attached to adjacent end flap 33 of the front panel 16. Thus when these portions are so glued and assembled, the panels 30, 31, 32 and 33 form corner posts of the box as shown in FIG. 1 and provide rigidity to the box even though the end panels or flaps 22 and 23 on the bottom panel 11 do not extend the full height of the ends of the box.

Only the front ends of the end flaps 24 and 25 of the top panel 12 are provided with diagonal crease lines 34 and 35, respectively, to form glued triangular portions attached to the end flaps 36 and 37, respectively, of the front lid panel 17. Since there are provided front posts by the flaps 31 and 33, it is not essential that these flaps 36 and 37 be the full length or height of the front panel 17.

These diagonal crease lines 26 through 29, 34, and 35 enable the box to be collapsed into the position shown in FIGS. 3, 4 and 5, by permitting these flaps to be folded inwardly.

Since there is a slight overlap of the end panel 22 with 24 and 23 with 25 as shown in FIG. 1, the flaps 24 and 25 may be provided with a pair of spaced notches 40 and 41, respectively, to provide between them a tuck-in flap portion 42 and 43, respectively, which may be locked-in over the top edge of the bottom end flaps 22 and 23 as shown in FIG. 1.

Furthermore the back panel 15 may be provided with ventilation apertures 45 if desired, as can any other panel of the box.

There is shown in FIGS. 6 and 7 another embodiment of this invention in which the blank for the carton or box is not provided with any locking tabs, nor are the flaps at the end of the front panel hinged to the top panel of shorter length. In this embodiment the blank 50 is completely rectangular and is only provided with slits and fold lines and no cut-out portions whatsoever, except for the apertures 85 for ventilation in the back panel 55. This blank 50 is provided with bottom and top equal rectangular panels 51 and 52 and between and on each side thereof are also provided equal rectangular back and front panels 55, 56, and 57 hinged together respectively along crease or fold lines 53 and 54 for the back panel 55 and crease lines 58 and 59 for the two front panels 56 and 57 hinged to the bottom and top panels 51 and 52, respectively.

All of the end flaps are similarly hinged to the central panels along parallel fold lines 60 and 61, and each of the end flaps extend out from these lines the same distance in opposite directions, which distance is a little more than half the height or width of the back panel 55, or the distance between fold lines 53 and 54. Thus the bottom panel 51 has end flaps 62 and 63, the top panel 52 has end flaps 64 and 65, the back panel 55 has end flaps 70 and 72, the front panel 56 has end flaps 71 and 73, and the front top flap panel 57 has full end flaps 76 and 77. Similarly as in the embodiment shown in FIG. 2, the end flaps 62 and 63 are provided with diagonal crease lines 66, 67, 68 and 69 at their corners to provide glued triangle portions which are attached to the end flaps 70 through 73 of the back and front panels which form the corner posts for the box as shown in FIG. 6. Also similar to the embodiment shown in FIG. 2, the top end panels 64 and 65 are only provided with diagonal crease lines 74 and 75 to provide glued trian-

gles which attach to the full end flaps 76 and 77 of the front top flap panel 57.

This box also may be collapsed after it is glued together in a fashion similar to that shown for the box 5 of the embodiment of FIGS. 1 and 2 as shown in FIGS. 3, 4 and 5.

It is to be clearly understood that the notches 40 and 41 shown in the embodiment of FIG. 2 may be added to the embodiments shown in FIGS. 6 and 7, and/or the half height end flaps 36 and 37 may be substituted for the full end flaps 76 and 77 shown in FIG. 7 without departing from the scope of this invention.

While there is described above the principles of this invention in connection with specific apparatus, it is to be clearly understood that this description is made only by way of example and not as a limitation to the scope of this invention.

What is claimed is:

1. A collapsible paperboard carton made from a single rectangular blank comprising:
  - A. equal rectangular bottom and top panels,
  - B. equal rectangular front and back panels, said back panel connecting said bottom and top panels by fold lines, and said front panel being connected by a fold line to the front side of said bottom panel,
  - C. a second rectangular front panel connected by a fold line to the front side of said top panel,
  - D. flaps connected by fold lines to the opposite ends of each of said panels and extending therefrom substantially about half the height of said back and front panels, said bottom panel end flaps each having two triangular creased corner portions glued to the adjacent end flaps of said equal front and back panels to form corner posts of said front and back panel end flaps that are as high as said front and back panels when said carton is set up.
2. A carton according to claim 1 wherein said second front panel connected to said top panel is equal to said front and back panels.
3. A carton according to claim 1 wherein said second front end flaps are about half the height of said second front panel.
4. A carton according to claim 1 wherein one of said panels is provided with at least one ventilation aperture.
5. A carton according to claim 4 wherein said back panel is provided with two spaced ventilation apertures.
6. A carton according to claim 1 wherein said end flaps on said top panel are provided with spaced notches between said corner posts to form tuck-in flaps between said notches for locking inside the top edge of said bottom end flaps when the carton is set up.
7. A carton according to claim 1 wherein said top panel end flaps each have one triangular creased corner portion glued to the adjacent end flaps of said second front panel.
